UNITED STATES PATENT OFFICE.

EMMA H. KING, OF NEWTON, AND JOSEPH H. CALDWELL, OF BOSTON,
MASSACHUSETTS, EXECUTORS OF CHARLES W. KING, DECEASED.

METHOD OF ASSEMBLING PARTS OF SHOES.

SPECIFICATION forming part of Letters Patent No. 774,523, dated November 8, 1904.

Original application filed October 25, 1894. Serial No. 526,974. Divided and this application filed April 5, 1901. Serial No. 54,405.
(No model.)

To all whom it may concern:

Be it known that CHARLES W. KING, deceased, a citizen of the United States, formerly a resident of Auburndale, Newton, in the 5 county of Middlesex, State of Massachusetts, did invent a new and useful Method of Assembling Parts of Shoes Preparatory to Lasting, of which the following is a specification, reference being had therein to the accompanying 10 drawings.

The present invention is designed to expedite and cheapen the process of manufacturing boots and shoes.

The invention consists in a new procedure 15 introduced in advance of the operations by which the lasting of a boot or shoe is effected and involving a succession of steps which assemble together certain of the prepared portions of a boot or shoe and secure them together in a shape and condition which facilitate the subsequent work. In substance the 20 steps of the said new procedure involve assembling together in proper relations with one another the inner sole, lining, counter, and 25 upper of a boot or shoe and securing these parts together at the heel only. The performance of these steps places the specified parts of a boot or shoe in a condition which enables them to be taken by the laster and be by him 30 immediately fitted and adjusted to a last and then to have the lasting operations performed in connection therewith. The said steps admit of being carried into effect almost exclusively by hand, although it will be obvious 35 that in practice the assistance of mechanical means will be utilized as far as possible. The precise nature of the said mechanical means is not material so far as the new method involving the invention is concerned.

40 The drawings of the present case show and the descriptive portion of the present specification describes mechanical aids which may be employed in carrying the method into effect if deemed advisable. The said mechanical aids are made the subject of claims in the 45 United States Letters Patent granted April 30, 1901, in the name of Charles W. King, for improvement in machines for assembling inner soles, linings, and counters of boots and

shoes, No. 672,624, of which this case is a division. 50

In the drawings, Figure 1 shows in front elevation the machine forming the subject of the pending patent aforesaid and which may be employed, if desired, in carrying the 55 present invention into effect. Fig. 2 shows in side elevation the upper part of the said machine. Fig. 3 shows the said machine in plan. Figs. 4 and 5 are sectional views of the upper portion of the machine on planes at 60 right angles to each other. Figs. 6 and 7 are detail views in section, respectively showing the pin-carrying plate and pins in the opposite positions thereof. Figs. 8, 9, 10, and 11 are views illustrating the steps of the method 65 in which the invention resides.

In the drawings, A represents a standard or column having a base B, on which are supported and carried the various operating parts of the machine. 70

C is a horizontal plate which is secured on the upper end of the standard A by screws D. This plate C is shaped in outline to conform generally to that of the edge of the heel portion of an inner sole, as shown in plan in Fig. 75 3, and the exterior of the standard for a short distance below the plate is shaped correspondingly.

Under the plate C is a recess or chamber E, and in this chamber is a horizontal plate 80 G, arranged to be moved up and down therein. The said plate G is secured by a central screw d on the upper end of a spindle H, which latter passes freely down through a vertical passage e in the transverse thickness 85 a of the standard, its lower end extending into a chamber J in the column, below the portion a, and being connected by a link K to an arm h of a lever L, pivoted on a cross pin or screw m in the standard and having a handle M extending out through the front opening of the chamber J for the actuation thereof. On swinging the handle M of lever L down the plate G is moved up, as shown in Fig. 7 in section, and on swinging the said 95 handle up the plate is moved down to its normal position, as shown in Fig. 6.

Secured in the plate G, around its curved

edge, is a series of vertical pointed pins N, of a length enabling them when the plate is in its normal or depressed position, as shown in section in Figs. 4 and 6, to project up into openings n in the fixed plate C. When this plate G is moved up into the position shown in section in Fig. 7, the pins will project above the plate, as shown.

P is an arm extending through an opening 10 r in the side of the standard into the chamber J of the standard and pivotally mounted within said chamber. At its upper end said arm has a right-angled projecting portion u, provided with a plate R of substantially the same 15 outline as the plate C, but preferably a little larger. The inner end of this arm P is formed with a transverse slot v, receiving a block S, through which the pivotal pin t extends, the arm being adapted to slide lengthwise on said 20 block and the block having a pin w, which projects up into a socket y in the arm. A spring z in said socket is compressed between the upper end of said pin and the inner end of a screw T, as shown more particularly in 25 Fig. 5.

The inner end of the arm P has on its edge a toothed segment U, the lower portion of which is concentric to the pin t, while its upper portion extends in a straight or vertical 30 line, as at a', Fig. 5. The said segment U engages with a vertical rack-bar V, adapted to slide up and down in a guideway b' in the inside of the column and connected by a pitman-rod Y to a treadle A', Fig. 1.

35 B' is a spiral spring connected by one end thereof to the treadle and by its other end to the lower end of the rack-bar V, as shown in Fig. 1. Pressing down the treadle A' pulls down the rack-bar V, which by its engagement with the segment-gear on the arm P first swings the arm forward and toward the standard into a vertical position, carrying its 40 plate R into position over and a little above the plate C on the upper end of the column, 45 after which the engagement of the rack-bar with the gear-teeth on the straight portion A' of the arm in the continued downward movement of the treadle and the rack-bar causes the arm P to move vertically downward until 50 its place R is close to or bears upon the plate.

The downward movement of the arm compresses the spring z, the arm sliding or moving over its pivot-block S. When the treadle is allowed to rise, the rack-bar moves up, carrying with it the arm P, and as the rack-bar 55 engages with the segmental gear in its continued upward movement it swings the arm P outward into its normal position, as shown in Figs. 1, 3, and 5. Through the plate R, 60 near its edge, is a series of holes or openings v', which when the arm is swung up into its true vertical position register with the holes in the plate C, so that when the plate R is in position over the column-plate, if then the pin-plate G is moved up, the pins N extending

through the holes in the plate C will also enter more or less the openings or holes v' in the plate R.

D' is an arm on the side of the column at right angles to the plate-arm P, pivoted upon 70 a cross-pin E' and having an angular extension w', in which is a slot F', through which passes a cross-pin G', mounted in the forked inner arm of a lever H', pivoted at y' between two lugs a' on the outside of the column and 75 having a handle b' for the operation thereof. The lugs a' are provided on a block Q, secured to the standard by the pivot-screw t of the arm P, the said screw passing through a vertical slot d' in the block. The block rests on 80 a vertical screw e', screwing up through a lug f' of the standard, by which the height of the lugs can be adjusted to regulate the height of the arm D' for its work. Attached to the upper end of this arm D' are two arms J', 85 projecting forward and having their inner edges curved, as shown in Figs. 3, 10, and 11. Pivoted at g' to each end of these arms J' are extensions or pieces K', which project still farther forward and are adapted to freely swing 90 to and from each other on their respective pivots. To press them toward each other, each arm K' has arranged in connection therewith a spring h', which bears against its outer side. Connected to each outer end of each of 95 these arms by a pivot L' is a chain or flexible band M', which extends back and is freely disposed in between the arms K' and K', as shown in plan view in Figs. 10 and 11 more particularly. Attached to each end of the chain is a 100 strip N', of leather, which extends along the inner side of the chain, as shown. On swinging forward the handle b' the arm D' is swung up until its curved arms J' are in a horizontal position, and in such position they embrace the 105 standard just below the plate C, as shown in dotted lines in Fig. 2 and Figs. 10 and 11. The arm is locked in such position by the cross-pin G' of the handle being at the outer 110 end of the slot F', the parts then being substantially at right angles to their pivots, which causes a lock of the several parts, preventing their movements of themselves; but by operating the handle all parts are moved back to 115 their normal positions again.

In carrying the invention into effect the procedure is substantially as follows, reference being had to Figs. 8, 9, 10, and 11: The mechanism being in its normal position, as shown in Figs. 1, 2, 3, 4, 5, and 6, the upper P' and its lining Q' inside are placed over the upper end of the column. Then the inner sole R' is introduced, as in Fig. 8, with its heel portion on top of the plate C, which supports the same. The treadle A' is depressed, 120 which pulls down the rack-bar V, swinging the arm P forward until its plate R is over the plate C and inner sole, and finally in the continued movement of the treadle the arm and its plate are pulled down so as to cause 125 130

- the said plate to press firmly down upon the heel of the inner sole. Then the handle M of the lever L is pressed down, which forces the pins N up through the inner sole, as shown 5 in Fig. 8. After this the treadle is released and allowed to rise, whereby the arm P is swung back out of the way into its original position. (Shown in Figs. 1, 3, and 5.) The edge of the lining Q' at the heel is then pulled 10 by hand over the edge of the inner sole at the heel and is pressed down over the upwardly-projecting pins, as shown in Fig. 9. The heel-counter S' is then placed over the inner sole and the lining thereon, with its sides or 15 edges inserted between the lining and upper and the bottom pressed down close to the lining. Then the handle b' is moved back, which swings up the arm D' and presses closely the flexible band M' around, about, and against 20 the sides and back of the upper at the heel, which holds the upper, lining, and counter firmly between the flexible band and standard. While the parts of the shoes are so held the lever L is swung up, which pulls the pins 25 N down, out from, and clear of the inner sole. With the upper, lining, and counter held, as described, by the flexible band, the corners n' of the counter S' held by the left hand of the operator close down upon the inner sole, 30 and the sides of the counter compressed by said hand against the column, a tack r' is driven through each corner of the counter into the lining and inner sole, as shown in Fig. 10, which secures them together at such points. 35 The upper and parts connected thereto can then be removed from the machine, being ready for lasting. If desired, before the upper is removed from the machine and before securing the counter by the tacks, the upper 40 can be brought by the fingers over the counter at its corners and tacks t' driven through the upper, the counter, the lining, and the inner sole at the corners of the counter, as shown in Fig. 11, which might be desired for 45 some lasting-machines, although generally it is sufficient to secure the counter to the inner sole without the upper.
- What is claimed is—
1. The method of assembling an inner sole, 50 lining and counter in connection with the upper of a boot or shoe preparatory to lasting, consisting in supporting the upper, placing the inner sole in position and holding it at the heel, pulling the lining over the edge of the
- inner sole at the heel and pressing it down 55 thereon, placing the heel-counter on the lining with its upper part between the lining and the upper, holding the upper, lining and counter along their sides at the heel against the edge of the inner sole, holding the corners 60 of the counter close down upon the lining and securing the lining and inner sole to and at each corner of the counter.
2. The method of assembling an inner sole, 65 lining and counter in connection with the upper of a boot or shoe preparatory to lasting, consisting in supporting the upper, placing the inner sole in position and holding it at the heel, piercing the inner sole, and providing projections above the upper surface thereof, 70 pulling the lining over the edge of the inner sole at the heel and pressing it down thereon over said projections, placing the heel-counter on the lining with its upper part between the lining and the upper, holding the upper, lining and counter along their sides at the heel against the edge of the inner sole, removing 75 said projections from the inner sole, holding the corners of the counter close down upon the lining and securing the lining and inner 80 sole to and at each corner of the counter.
3. The improvement in the art of manufacturing boots and shoes, which consists in taking an upper with the lining therein, placing the inner sole inside the lining in proper position, pulling the edge of the lining over the edge of the inner sole, placing the heel-counter on the lining and inner sole at the heel with its upper part between the lining and the upper, holding the upper, lining and counter 85 90 along its sides against the edge of the inner sole at the heel, and the corners of the counter close down upon the lining, and securing the lining, inner sole and counter together to and at each corner of the counter.

In testimony whereof we have signed our names to this specification each in the presence of two subscribing witnesses.
